UNITED STATES PATENT OFFICE.

EDWARD L. McDIVITT AND WILLIS S. BROWN, OF BELVIDERE, ILLINOIS,
ASSIGNORS TO THE NATIONAL SEWING MACHINE COMPANY, OF SAME
PLACE.

DESIGN FOR A VELOCIPED-CRANK.

SPECIFICATION forming part of Design No. 27,552, dated August 17, 1897.

Application filed May 22, 1897. Serial No. 637,790. Term of patent 14 years.

To all whom it may concern:

Be it known that we, EDWARD L. McDIVITT and WILLIS S. BROWN, citizens of the United States, residing at Belvidere, in the county 5 of Boone and State of Illinois, have invented and produced a certain new and original Design or Useful Shape for Velocipede-Cranks, of which the following, taken in connection with the accompanying drawings, is a full, 10 clear, and exact specification.

In the said drawings, Figure 1 is a side elevation of a velocipede-crank made in accordance with our invention. Fig. 2 is a transverse sectional view taken on the line 2 2, 15 Fig. 1; and Fig. 3 is a transverse sectional view taken on the line 3 3, Fig. 1.

The leading features of our design consist of a bicycle-crank having a hub-like portion A projecting laterally from one end thereof 20 and being tapered from the main crank portion B toward its outer end and having disposed around its periphery a number of longitudinal ribs or corrugations C.

The main crank portion B, as shown in the 25 drawings, is of tapering form, growing larger toward the hub A, and gradually rounds off at its extremity by the curve b toward a shoulder b', which constitutes the inner end of the hub-like portion A, but, as shown in 30 Fig. 1, the hub-like portion A is of slightly less diameter than the shoulder b'. The hub-like portion A extends substantially at right angles to the main crank portion B and tapers

toward its outer extremity, which latter, however, has a cylindrical extension a, perforated 35 by a transverse passage a'.

The periphery of the conical or tapering hub-like portion A is provided with a number of longitudinal ribs or alternately depressed and raised portions, which extend from the 40 shoulder b' to the beginning of the cylindrical portion a. These corrugations are disposed substantially equidistant apart around the hub A, as shown in Fig. 2, and the raised portions or ribs C are each of an oblong form-- 45 that is to say, of the same thickness or width from end to end--while the depressions or portions of the hub between the ribs C are of tapering form like the hub. The ribs C are also of the same depth from end to end--that 50 is, the same thickness in a direction toward the axis of the hub.

The upper or inner ends of the ribs C are flat and even with the circumference of the inner end of the hub A, as shown at c. 55

Having thus described our invention, what we claim as new, and desire to secure by Letters Patent, is—

The new and original design or useful shape for a velocipede-crank substantially 60 as herein shown and described.

E. L. McDIVITT.
WILLIS S. BROWN.
